BED FRAME OR THE LIKE

Justin J. Wetzler, Evanston, Ill., assignor to The Englander Company, Inc., Chicago, Ill., a corporation of Illinois

Application April 6, 1955, Serial No. 35,389

Term of patent 14 years

(Cl. D5—4)

The figure is a perspective view of a bed frame or the like embodying my new design.

The design is characterized by the vertical disposition and substantially uniform vertical extent of the peripheral frame and the enclosed corner braces and transverse members.

The dominant features of my design reside in the portion shown in full lines.

I claim:

The ornamental design for a bed frame or the like, substantially as shown and described.
